[57] CLAIM

The ornamental design for a slide mount bracket for a
radio and the like, as shown and described.

DESCRIPTION

FIG. 1 is a perspective view of the slide mount bracket
showing my new design;

FIG. 2 is a top plan view thereof on a reduced scale;

FIG. 3 is a bottom plan view thereof on a reduced scale;

FIG. 4 is a front elevational view thereof on a reduced
scale;

FIG. 5 is a rear elevational view thereof on a reduced
scale;

FIG. 6 is a right side elevational view thereof on a
reduced scale; and

FIG. 7 is a left side elevational view thereof on a re-
duced scale.

The broken lines in the drawing are for illustrative
purposes only.
